UNITED STATES PATENT OFFICE.

EUGENE D. BATES, OF PHILADELPHIA, PENNSYLVANIA.

FLAGSTAFF-BRACKET.

SPECIFICATION forming part of Letters Patent No. 655,951, dated August 14, 1900.

Application filed January 24, 1900. Serial No. 2,635. (No model.)

To all whom it may concern:

Be it known that I, EUGENE D. BATES, a citizen of the United States, and a resident of the city and county of Philadelphia, State of Pennsylvania, have invented certain new and useful Improvements in Flagstaff-Brackets, of which the following is a specification.

My invention relates to improvements in brackets for holding flagstaffs, &c.; and the objects of my invention are, first, to furnish a bracket for this purpose which will receive and tightly hold staffs of widely-varying diameters, and, second, to furnish an improved means whereby the staff may be quickly and positively locked to the bracket and as quickly released.

My invention is illustrated in the accompanying drawings, in which—

Figure 1 is a perspective view of my improved bracket, showing the lower end of a flagstaff engaged thereby; and Fig. 2, a section through the movable keeper, showing the swivel attachment of the operating - screw therewith.

25 My bracket *a* is furnished with a foot *b*, which may be secured by screws or otherwise to any suitable support—a window-sill, for instance.

30 *c d* are V-shaped rests, the former at the outer and the latter at the inner end of the bracket.

e is an open standard situated about midway between rests *c d* and preferably pivoted at its bottom to the bracket *a*, through which

35 the staff passes. This standard carries a vertically-movable keeper *f*, which is furnished with slots *g*, through which the sides of standard *e* pass.

40 *h* is a screw passing through top of standard *e* and preferably connected with keeper *f* by means of a swivel, as shown in Fig. 2, by means of which the keeper may be forced down against the top of the staff, the lower side of which rests in the V-shaped rests *c d*.

45 *i* is a cleat forming part of the casting of bracket *a*, upon which the flag-halyards may be secured and which takes the place of the separate cleat usually employed for this purpose.

A bracket of this construction will receive 50 and hold staffs of widely-varying diameters; the smaller sizes of brackets taking staffs of from one-half an inch to two and one-half inches in diameter, the diameter of staff that the device will carry being principally limited 55 by the size of opening in standard *e* and to a minor extent by the size of the rests *c d*. It will be seen that the rests *c d* and the standard *e* may be made of any size desired, each size being capable of receiving staffs of widely- 60 varying diameter.

Having thus described my invention, I claim—

1. In a flagstaff-bracket, in combination, V-shaped rests, formed integrally with the 65 bracket, for supporting the under side of the staff, a standard, placed between the rests and pivoted at its lower end to the bracket, through which the staff passes, and a screw carried by the upper end of said standard adapted to engage the top of said staff.

2. In a flagstaff-bracket, in combination, V-shaped rests, formed integrally with the bracket, for supporting the under side of the staff, a standard, placed between the rests and pivoted at its lower end to the bracket, through which the staff passes, a vertically-movable keeper, the ends of which are guided by the sides of said standard, adapted to engage the top of the staff, and a screw passing through 70 the top of said standard and adapted to force said keeper against the upper side of said staff.

3. In a flagstaff-bracket, in combination, rests adapted to engage the under side of the 85 staff, a standard placed between the rests and pivoted to the bracket at its lower end, a vertically-movable keeper, furnished at its ends with slots through which the sides of said standard pass, adapted to engage the upper 90 side of the staff, and a screw passing through the upper end of said standard and swiveled to said keeper.

EUGENE D. BATES.
